8 Claims. (Cl. 263—46)

The present invention relates to an improved hearth-type furnace, particularly a Siemens-Martin furnace.

In a Siemens-Martin furnace the fuel and the combustion air come together at the burner head. It is advantageous from the standpoint of flow technique considerations to introduce the combustion air as near as possible to the fuel jet. Additionally, it is also desirable for the combustion and flame direction or regulation to impart to the air current a specific impulse for which it is necessary to have a suitable air velocity and a correspondingly smaller outlet cross-section for the air. For these reasons the inside width of the burner head is always smaller than the inside width of the adjoining heating chamber.

The transition from the back wall and the front wall to the side walls of the burner head form the so-called hearth pillars, which are vertical or nearly vertical walls which enclose an acute angle with the longitudinal axis of the furnace and constrict the cross-section of the heating chamber towards the burner head. With specific burner head constructions the hearth roof or dome must also be pulled or directed down towards the burner head and the annexing burner head dome must be arranged at an inclination to the hearth. The slopingly arranged hearth pillars and the inclined domes at the transition from the burner head to the hearth are advantageous for the flow process of the combustion air and the flames. However, they form at the escape or draw-off side of the furnace a constrictive region for the stream of smoke gas and, thus, are subjected to pronounced wear. The slopingly arranged hearth pillars and the inclined dome sections have still a further disadvantage which always becomes more readily discernable: The brickwork of the superstructure of the furnace must always be renewed in periods of several months to a year. The influence of the furnace preparation or lining costs on the production costs for steel is always becoming greater with the continuous increase of wages. For this reason, in the furnace construction art, it is attempted to get along with as few and simple brick forms as possible, to reduce the storage of refractory material, to limit the trim work during the furnace preparation or lining operation, and for such reasons to make the furnace shape as simple as possible.

It has already been proposed in the art to impart to the superstructure of the furnace a box-type shape, to build the burner heads with the same inner width as the heating chamber and to construct the side walls of the burner head in the form of linear extensions of the forward and back or rear walls while dispensing with the hearth pillars. Additionally, the disposing of the inclination of individual dome sections is always more and more desired. In the previously undertaken proposed simplifications one know-

2

ingly accepted flow technique disadvantages which unfavorably influenced the course of combustion and the direction of the flame path. In particular, it was not possible to find a satisfactory solution for the arrangement and construction of the shafts.

In accordance with the proposals known at the present time, the width of the burner head is brought to the width of the heating chamber and the forward and rear end shaft walls are moved away from one another to the same extent so that these shaft walls and the side walls of the burner head remain in a plane. As a result, there is engendered a series of disadvantages. The separation of both shafts with double shaft furnaces, or the enlargement of the shaft with a single shaft furnace, to the width of the heating chamber, of necessity, requires a longer slag pocket or chamber than usual. The elongation of the slag pocket increases construction costs of the furnace and, in many, if not in the majority of steel mills, is not at all possible to carry out because with the elongation of the slag chamber the checker chamber must also be further displaced towards the reversal equipment and the available space in the steel mills, only in the most rare instances, permits such a displacement.

In a single shaft furnace such an expansion or enlargement of the shaft results in unequal air impingement at the cross-section of the shaft, because the air from the slag chamber of the shaft is not directed in the direction of the lengthwise axis of the hearth, but rather, is directed at a right angle thereto. The front wall side portion of the shaft receives less air than the rear wall side and this irregularity is continued to the heating chamber, in which the flame at the one side burns with excess air and at the other side with a deficiency of air. The irregular air distribution can also lead to a deflection of the flame toward the rear wall and to greater wear of this furnace portion. The greater the width of the air shaft, then the greater the distance that the combustion air must be sucked up by the oil burner, then also the greater the tendency for the burner to work as injector upon the smoke gases located in the heating chamber. The trail of the smoke gases becomes larger, the flame temperatures lowered and the service life of the lining lowered, because due to the trail of the smoke gases always new FeO-particles are guided to the refractory lining. A further disadvantage of such a wide shaft resides in the large dimensions of the shaft reflecting walls, the durability of which decreases and the brick consumption of which increases.

A portion of the enumerated disadvantages also occurs with the previous proposed widening of the burner head of a double shaft furnace. In this case there is also present as a further disadvantage the widening of the flame bridge between the air shafts, the wider it is that much more dust and slag deposit, and with increasing width becomes very difficult to maintain clean.

Accordingly, the present invention has as one of its primary objects to effectively prevent or minimize such disadvantages.

A further important object of the present invention is to provide an improved construction of a hearth-type furnace, in particular a Siemens-Martin furnace, which is economical to construct and repair, permits the use

of a small number of brick shapes for the furnace superstructure so that the storage of such bricks and the supporting structure therefor is considerably simplified.

Another important object of the present invention is to provide an improved construction of a hearth-type furnace permitting the latter to assume a substantially box-shaped configuration, thereby facilitating relining of the furnace and generally improving the economics of production and maintenance of such furnace.

A further important object of the present invention is the provision of a Siemens-Martin furnace or the like, wherein the cross-section of the furnace superstructure with the exception of the base is substantially uniform from one end wall to the other.

Still another important object of the present invention is the provision of a Siemens-Martin furnace or the like, wherein the inner width between the forward and back walls or outermost walls of the shaft means closest to the respective forward and back walls of the furnace superstructure is smaller than the inner width of the burner head of the aforesaid furnace superstructure as measured at the plane of the mouth or opening of said shaft means.

The furnace of the present invention is characterized by the features that the cross-section of the superstructure of the furnace with the exception of the hearth base, remains continuously the same from end wall to end wall, that the front wall and rear wall are inwardly inclined and the inner spacing between the forward wall side and the rear wall side of the shaft means is smaller than the inner width of the burner head profile, measured at the plane of the mouth of the shaft means.

The blind angle or space between the opening or mouth of the shaft and the receding burner head walls can, for example, be filled with a granular refractory material. The burner head thereby has imparted to it, apart from the hearth base, the same profile as the heating chamber, whereby the side walls of the burner head at their crown or top possess approximately the same spacing as the forward and rear side walls of the shafts. In other words, the spacing of the forward and rear side walls of the shafts substantially corresponds to the width of the furnace dome.

The form, size and position of the shafts, the opposite situated dome and the upper portion of the side walls of the burner head are determinative for the guiding of the combustion air. Since the position and form of the shafts remains unchanged and by virtue of the inward inclination of the side walls of the burner head their spacing at the top in comparison with the classical constructional forms also does not experience any marked change, the flow process in the working or outlet side of the burner head is not disadvantageously influenced in spite of the separation of the burner head walls at the base.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

In the drawings wherein like reference numerals generally denote similar elements:

FIGURE 1 illustrates a fragmentary, cross-sectional view taken along lines I—I of the furnace of FIGURE 2;

FIGURE 2 is a fragmentary, cross-sectional view taken along the lines II—II of FIGURE 1;

FIGURE 3 is a cross-sectional view taken along lines III—III of FIGURE 2;

FIGURE 4 is a cross-sectional view taken along lines IV—IV of FIGURE 2;

FIGURE 5 is a fragmentary view showing details of a modified form of furnace port end, particularly a furnace

with an inclined burner head and inclined shaft means;

FIGURE 6 is a fragmentary view showing details of a further design of furnace port end, wherein the shaft is vertical and the end walls of the furnace are inclined; and

FIGURE 7 is a cross-sectional view substantially similar to FIGURE 4, illustrating details of the brickwork and support structure.

In the drawings there is generally illustrated the furnace superstructure of a reverberatory hearth-type furnace, particularly a Siemens-Martin furnace, provided by way of illustration and not limitation, with a double-shaft or uptake, and depicting the relatively simple furnace shape achieved by following the teachings and underlying principles of the present invention. For purposes

of simplifying the explanation and illustration of the invention, only enough of the furnace structure has been shown to enable one skilled in the art to readily appreciate the inventive concepts and to fully understand the description to follow.

Describing now FIGURES 1 to 4, reference numeral

1 generally denotes the hearth brickwork of the superstructure of the furnace F to which is connected side walls in the form of a forward wall 2 and a rear or back wall 3, both of which are inwardly inclined, as best seen in FIGURES 2 and 3. Between both of the side walls 2 and 3 there extends the roof or dome 4. Directly adjacent to and flush with one end wall 5 there extends into the furnace or heating chamber 7 a pair of air shafts or upstrokes 6. The shafts 6 open into the burner head region, generally designated by numeral 10, at a plane A—A taken through the respective opening or mouth of said shafts. The region of the furnace superstructure lying beneath the plane A—A can be conveniently considered as the base portion of the aforesaid superstructure.

Both of the side walls 2 and 3 advantageously extend from one end wall 5 to the other end wall (not shown) with the same inclination and the same curvature. For convenience in illustration there is only shown one end of the furnace superstructure, but it is to be appreciated, and as will be apparent to those skilled in the art, a substantially similar arrangement of shafts and burner head are provided at the opposed port end of the furnace. The height of the walls 2 and 3 is advantageously the same throughout the entire length of the furnace, as can be readily ascertained by comparing FIGURES 3 and 4.

Thus, for the construction of the forward and rear walls 2 and 3, respectively, only a single brick shape or format is necessary. This is also true for the dome 4, likewise constructed from end wall to end wall of the furnace with the same curvature and the same width. The parting surfaces between the brick assembly of the walls 2, 3 and that of the dome 4 lie at the same height, that is, all individual parting surfaces between the corresponding walls 2, 3 and dome 4 form a plane, as generally indicated in FIGURES 3 and 4 by the lines B—B and C—C.

In the embodiment illustrated in FIGURES 1 to 4, the walls of the shaft means 6 here depicted for example as a double-shaft arrangement, are inclined as shown, to provide the proper direction of air inflow, as will be further explained shortly hereinafter. The outermost walls 6a and 6b of the shafts 6, that is, the respective walls of the shafts closest to and extending in substantially the direction of the front and rear walls 2 and 3, respectively, are spaced from one another at an inner distance or width X which is less than the inner width Y of the profile of the burner head 10 (see FIGURE 3), as measured in the plane A—A of the mouths of the shafts 6 as well as substantially corresponding to the width of the dome 4. In other words, the outermost walls of the shaft means 6 are spaced from one another

65 to provide an inner width or spacing X which is less than the inner width or spacing Y of the front and rear walls of the burner head 10 of the furnace superstructure, as measured along the plane A—A of the mouth of the shaft means 6, that is, the location where the latter open into

the burner head 10. In the event of a single shaft arrangement this aforementioned relationship would also be maintained. The dead spaces or blind angle 13 between the outermost walls 6a, 6b of the shafts 6 and the associated side walls 2, 3 can advantageously be filled, if desired, with a granular refractory material, as indicated, at 14, in FIGURE 3.

The angle between the air currents out of the shafts 6 and the dome 4 above said shafts is of importance for the flow process of the combustion air. This angle should not exceed a specific value. In order to maintain such angle with the desired limits, the shafts 6 are advantageously positioned to be inclined with a dome having horizontal zenithal or top lines, for example as shown in the arrangement of FIGURE 1. The end wall 5 of the furnace can remain vertical, in the manner shown. However, it is also possible that such end wall receive the same inclination as the shafts. Such an arrangement is shown, by way of example, in FIGURE 5 wherein the walls 6c of the double shaft means 6d are inclined and merge with a furnace end wall 5a which is similarly inclined. It is, however, also possible to leave the shaft means perpendicular and only to inwardly incline the end wall, since then also the angle of impact between the air currents which emanate from the shaft means and the dome is smaller than 90°. Such an arrangement is shown, by way of example, in FIGURE 6 wherein the double shaft means 6e is provided with vertical shaft walls 6f merging with an inwardly inclined end wall 5b of the furnace.

In FIGURE 7 there are depicted details of the support arrangement for the front and rear walls 2 and 3, respectively, as well as the dome 4 of the furnace superstructure. Advantageously, the walls 2, 3 and dome 4 are formed of suitable brickwork 15 arranged in individual sections or groups 20. These brickwork sections 20 are arranged alongside one another and extend the length of the furnace (see FIGURES 1 and 2). The brickwork of each section of the walls 2, 3 and 4 are advantageously supported by individual segments or elements 16, 17 and 18, respectively, with the support elements of any one wall being similar to one another and interchangeable. The support elements 16, 17 and 18 of each brickwork section are suspended on I-beam 19 or the like extending lengthwise of the furnace. For further details of such a possible support arrangement for the furnace brickwork, attention is directed to the commonly assigned, United States Patent No. 3,088,722, granted May 7, 1963, to Alfred Slesaczek for "Wall Construction and Mounting Thereof for Industrial Furnaces." Particular advantages result with the reinforcement or armament of the furnace, especially then, when the walls 2, 3 and the dome 4 are assembled from prefabricated brickwork strips. The individual steel segments 17 of the dome 4 at which the bricks 15 are suspended are advantageously similar to one another, as are the support segments 16 and 18 for the side walls 2 and 3 respectively. Such an arrangement has the result of providing a considerable simplification of the furnace construction, of the storage of materials, and a mutual interchangeability of the individual segments of each wall section.

While there is shown and described present preferred embodiments of the invention, it is to be distinctly understood that the invention is not limited thereto but may be otherwise variously embodied and practised within the scope of the following claims.

Having thus described the present invention, what is desired to be secured by United States Letters Patent, is:

1. Hearth-type furnace including a furnace superstructure provided with a front wall, a rear wall, a dome and opposed end walls, said front and rear wall being inwardly inclined, said walls defining a space of substantially constant cross section from one end wall to the other end wall, shaft means of relatively small cross-section communicating with said space beneath said dome,

said shaft means having outermost walls extending substantially in the direction of said front and rear wall, with the spacing between said outermost walls being less than the spacing between said front and rear wall of said furnace superstructure and substantially corresponding to the width of the dome.

2. Siemens-Martin furnace including a furnace superstructure comprising a front wall, a rear wall, a dome and opposed end walls, said front and rear wall being inwardly inclined, said furnace superstructure having an upper portion and a base portion, said upper portion being of substantially constant cross-section from one end wall to the other and wall, double shaft means opening from below into said upper portion beneath said dome, said double-shaft means including outermost walls extending substantially in the direction of said front and rear wall, the spacing between said outermost walls being less than the inner spacing between said front and rear wall of said furnace superstructure and substantially corresponding to the width of the dome.

3. Siemens-Martin furnace including a furnace superstructure having a front wall, a rear wall, a dome and opposed end walls, said furnace superstructure including at least one burner head and a heating chamber, double shaft means including mouth means opening into said burner head beneath said dome, said mouth means being flush with the associated end wall, the portion of the furnace superstructure disposed beneath a plane containing said mouth means of said shaft means defining the base of said furnace superstructure, the cross-section of said furnace superstructure above said plane and extending from one said end wall to the other being substantially constant throughout, said double-shaft means being defined by outer walls extending in the direction of said front and rear wall which are spaced from one another a distance less than the inner width of said burner head between said front and rear wall measured along said plane of said mouth means and approximately corresponding to the width of said dome.

4. Siemens-Martin furnace including a furnace superstructure provided with a front wall, a rear wall, a dome and opposed end walls, said front and rear wall being inwardly inclined and formed of bricks arranged in sections alongside one another, prefabricated support elements for carrying said bricks of each section, said prefabricated support elements of any one front and rear wall being similar to one another and interchangeable, said furnace superstructure comprising at least one burner head, a heating chamber and a base portion, the portion of said furnace superstructure disposed above said base possessing a substantially uniform cross section from one end wall to the other end wall, double-shaft means including mouth means opening from below into burner head beneath said dome, said double-shaft means being of relatively small cross-section to provide relatively high flow velocities for air and are bounded by outer walls extending in the direction of said front and rear wall, said outer walls being spaced from one another a distance substantially equal to the width of the dome as well as a distance less than the inner width of said burner head between said front and rear wall measured along a plane containing said mouth means.

5. Siemens-Martin furnace according to claim 4 wherein said double-shaft means are inclined in the direction of said heating chamber.

6. Siemens-Martin furnace according to claim 4 wherein said double-shaft means are vertical and the end wall of the associated burner head is inclined in the direction of said heating chamber.

7. Siemens-Martin furnace according to claim 4 wherein said double-shaft means and the end wall of the associated burner head are inclined in the direction of said heating chamber.

8. Siemens-Martin furnace according to claim 4 wherein said dome is formed of bricks arranged in sections along-

side one another, prefabricated support elements for carrying said bricks of each dome section, said prefabricated support elements for any one dome section being similar to one another and interchangeable.
